Fig. A.

Fig 5

Fig. 6

A technical line drawing of a bridge deck structure. The drawing shows a top horizontal beam supported by vertical columns. Below the columns is a horizontal beam. The structure is divided into sections by vertical lines. The leftmost section is labeled '18'. Above the first two sections, there are two labels: '24' above the first and '4' below the second. The third section is labeled '10'. Above the fourth section, there are two labels: '24' above the first and '4' below the second. The drawing uses dashed lines to indicate hidden parts of the structure.

Delaware

Application September 11, 1931, Serial No. 562,372

3 Claims. (Cl. 105—366)

This invention relates to improvements in container cars and containers therefor, and particularly to container cars of drop-side type and containers designed for use in connection therewith. 5 One object of the invention is to provide a construction and arrangement of container holding compartments in a drop side container car and containers adapted to be received therein, whereby a comparatively large number of compartments may be furnished and the containers arranged in transverse pairs in the compartments. 10

Another object of the invention is to provide a construction of container car with auxiliary guides or abutments which facilitate the placing 15 of the containers in position, or their removal, while effectually preventing shifting of the same on the car during transit.

Still another object of the invention is to provide a construction of container car whereby a 20 standard type car having comparatively long and wide compartments for holding a limited number of large size containers may be converted at a low cost into a type of car for holding a larger number of smaller containers arranged in transverse rows of a pair or greater number of containers than a pair in each row.

A still further object of the invention is to provide auxiliary longitudinal-shift-preventing attachments for application to a standard container car adapted to receive containers of a predetermined large size, each of the same width as the normally wide compartment and of a length equal to the width of the car, whereby the width 30 of a container receiving compartment may be decreased from full width to a predetermined narrower width so as to receive and hold a single container of less width than a container of the predetermined full width but equal in length to the width of the car, or to receive two transversely aligned containers of the predetermined narrow width and each of a length substantially half the width of the car, whereby through the use or non-use of the auxiliary longitudinal-shift-preventing attachments, the container compartments 40 may be rendered effective to hold containers of different sizes and suitable for containing different sized articles or different commodities.

With these and other objects in view, the invention consists of the features of construction, combination and arrangement of parts, herein-after fully described and claimed, reference being had to the accompanying drawings, in 50 which:—

Fig. 1 is a top plan view of a container car body and containers embodying my invention.

Fig. 2 is a side elevation of the car body and containers, showing one of the drop doors in let-down position. 5

Fig. 3 is a front elevation of one of the containers.

Fig. 4 is a fragmentary top plan view of a container car showing a mode of converting a standard container car into a container car designed 10 to hold containers arranged in accordance with the present invention.

Fig. 5 is a section on line 5—5 of Fig. 4.

Fig. 6 is a section on line 6—6 of Fig. 4.

Fig. 7 is a section on line 7—7 of Fig. 4. 15

Referring now more particularly to the drawings, 1 designates a container car of drop-side type, having a floor 2, stationary end walls 3, and transverse intermediate walls, bulkheads or partitions 4 forming with the walls 3 compartments 20 5, each compartment being normally open to provide a doorway for the compartment at each side of the car. Each doorway is adapted to be closed by a door or gate 6 hinged at its lower edge so as to be swung upwardly to a closed position 25 and downwardly to an open position, each door being provided with suitable latches or fastening means to engage keepers on posts forming portions of the bulkheads 4 at the sides of the doorway. The doors 6 may be so mounted that they 30 may be swung downward to a vertical position or they may be so mounted that they may swing downward to a horizontal position to serve as gangways or loading platforms to bridge the spaces between the compartments and a loading 35 station or stationary platform alongside the track on which the car is disposed. The compartments are, as customary, of comparatively shallow depth to receive only the lower portions of the container 7 to be mounted therein, but they may be 40 of any depth desired as circumstances or conditions may require in practice.

Each container 7 is of rectangular or oblong rectangular form and of special construction, and comprises a steel-framed, steel-sheathed water-proof container provided with depending supporting legs 8 at the four corners of the bottom thereof, lifting brackets 9 at the four corners of the top thereof, and hinged doors 10 at the front, which doors are adapted to be secured in closed 50 position by a vertically disposed, oscillatory locking bar 11 mounted on one of the doors and carrying at its ends bolts 12 to engage keepers 13 on the container above and below the doorway. Any suitable means may be employed for oscil- 55

lating the bar 11, a hand lever 14 being shown in the present instance as provided for that purpose, said lever being also apertured to serve as a locking staple for engagement with a keeper eye 15 on the other door. A hook 16 carried by one end of a chain 17 fastened at its opposite end to the door carrying the keeper eye is shown as provided for engagement with the eye to hold the staple in locking position, but a padlock or other locking means may be employed for the purpose, and, if desired, a suitable type of seal may be used which must be broken before the doors can be opened to allow access to the container, and the breakage of which will indicate that the fastening means has been tampered with or released.

The drawings show a container car of standard type in which the end walls 3 and bulkheads 4 are spaced to form compartments 5 each of a width to receive a single container of a predetermined standard large size, that is, of such a width as to fit within such a compartment and of the same length as the width of the car. Each container 7 herein shown is of less width than such a standard large container and also of less length than such a standard large container, namely, of approximately one-half the length of a standard container, so that two containers 7 may be placed in transverse alignment in each compartment instead of a single large container corresponding in length to the width of the car. In order to adapt these smaller sized containers to be used in one, two or more or all of the compartments of a standard car I provide auxiliary sockets properly arranged to receive the legs of the smaller containers and position the same in the compartments, and I also provide novel auxiliary abutments or longitudinal-shift-preventing attachments to suitably reduce the widths of the compartments to properly receive the smaller sized containers 7 and to prevent the same from shifting longitudinally of the car. All compartments of the car may be provided with a full complement of sets of standard and auxiliary leg receiving sockets as permanent fixtures, but the longitudinal-shift-preventing attachments may be used or not, as required. According to the number of the compartments in which these attachments are used, the car may be adapted to hold containers all of a given small size, or certain of the compartments may be equipped with the attachments to hold small sized containers or left unequipped with them, so that both standard and small sized containers may be carried on one and the same car. The longitudinal-shift-preventing attachments are so constructed that they may be readily and conveniently applied and removed so as to render the car interchangeable for use in transporting either a full complement of standard or small sized containers or a mixed complement of standard and small sized containers, varying in number relative to each other, according to service demands.

I will first describe the arrangement of the auxiliary sockets and then the construction and use of the longitudinal-shift-preventing attachments for converting the compartments of the car at will from standard-width to narrower-width compartments, or vice versa.

The legs 8 are adapted to seat within sets of auxiliary receiving sockets 18, 18a and 19, 19a provided for their reception in the compartments 5, each socket being secured to the top of the floor 2 or fastened in depressions therein and be-

ing adapted to loosely receive the lower ends of the legs so that the container may be fitted down into position without interference and in a ready and convenient manner. As shown particularly in Fig. 4, eight such auxiliary sockets are provided in each compartment 5, four on each side of the longitudinal center of the car, and so disposed that each compartment, when properly decreased in width from original size, as hereinafter described, will contain a pair of transversely disposed containers 7, which containers may be loaded and unloaded from either side of the car. The legs 8 are provided with guide shoes 8' for guiding contact with the doors and other surfaces in guiding the containers into and out of position, and the sides of the containers may be provided with suitable reinforcing and guiding ribs 20 for engagement with guide bars 21 at the sides of each compartment to further assist in guiding the container into and out of position.

In a standard type of drop-side container car, of approximately fifty foot length, such as shown, the car is divided by bulkheads into six compartments, extending from side to side thereof, and each container is of a width and length sufficient to fully occupy an entire compartment. Such compartments and containers are of excessive size for the purposes for which the present invention is designed, and is is therefore necessary to decrease the width of the container compartments, with respect to standard width, and to provide a suitable arrangement of auxiliary containers receiving sockets in order that two containers of reduced size with respect to standard size may be disposed in each compartment. Cars expressly constructed for the purposes of the present invention may, of course, be provided and are, in fact, in use, but I have shown in Figs. 4 to 7, inclusive, a type of construction for converting a standard car into a car having the necessary number of smaller compartments to receive containers arranged in transverse pairs, without the necessity of altering the body construction of the car. In thus converting a standard car attachments in the form of transverse guide bars 45 or rails serving as auxiliary abutments or longitudinal-shift-preventing devices are provided. The guide bar 21 of each end compartment 5 adjacent to the stationary end wall 3 is mounted on posts 22 spaced inwardly from the end wall 3 and secured to and reinforced from the end wall at their upper ends by bracing and distance blocks 23, while the guide bars or rails adjacent the bulkheads 4 are similarly mounted on posts 24 and reinforced and spaced at their upper ends 55 from the bulkheads by distance blocks 25, by which means the compartments, which are normally of a width equal to the distance between each end wall and the adjacent bulkhead and between adjacent bulkheads, are reduced in 60 width without removal of floor or bulkheads or otherwise reconstructing the original body structure of the car. The original sockets provided to receive the legs of the standard large size containers, which are recessed into the floor 2, are 65 here indicated at 26 in their original positions in which, as shown, they underlie the posts 22 and 24. Preferably in converting the large compartments into small compartments these sockets 26 are closed by filler blocks 27 which form pedestals 70 or seats for the posts and to which may be secured angle irons 28 for firmly securing and bracing the posts in position. By making the parts 21, 22 and 23 detachable, one and the same container car may be used as a standard container 75

car and converted at will into a car having the increased number of compartments of reduced size for receiving the container 7.

It will thus be seen that by the use of the attachment elements comprising the auxiliary abutment rails and the means described for stably but separably fastening the same to the car floor and the car end walls permanent abutments 4, the width of any compartment 3 may be reduced from standard width to a narrower width suitable for holding containers of less width than standard large-sized containers without in any manner changing the permanent construction of the car. Also that by the use of the auxiliary sockets 18, 18a, 19, 19a provision is made for the proper positioning in each compartment so narrowed of two transversely aligned containers 7, each of a length substantially equal to one half of the width of the car, so that the abutment rails 21 will hold such containers against shifting longitudinally of the car, while the auxiliary sockets hold them from shifting transversely of the car. Such provision of the attachment rails 21 and auxiliary sockets further allows a single container of a width corresponding to the width of the narrowed compartment but of a length equal to the width of the car by seating the legs of such a container in the outer sets of sockets 18 and 19, should it be desired to use containers of less than standard width but of standard length. In this case, of course, the intermediate sockets 18a, 18a, 19a, 19a would not be used, but their presence allows either a single narrow, full-length container or a pair of containers 7 to be interchangeably used in each compartment equipped with the auxiliary abutment rails and sockets. Also it will be seen that by simply removing the attachment rails 21 of any one or more of the compartments the original condition of the compartments, adapting them to again receive full-sized containers, will be restored.

By this means a car built to receive standard containers of large size, one in each compartment, can be converted to hold in each compartment a single container of full length but reduced width with respect to standard size, or to hold in each compartment two small containers, such as the containers 7, and by modifying some, but not all, of the compartments in the manner described, the car may be adapted to carry a mixed complement of containers of different sizes. An important feature of the invention is that by the use of the attachment rails mounted in the manner described these rails lie parallel with and at the same level as the abutments 4, so that they take the place of the abutments to fully perform the functions thereof, that is, not only to hold a container from longitudinal shifting but also to guide the container into and out of the compartment in loading and unloading actions, whether the container be moved vertically or laterally into and out of the compartment. The attachments thus provide simple and effective means for converting the compartments of a standard container car to adapt the same to hold different sized containers without the necessity of mutilating or reconstructing the car or modifying any of its permanent fixtures.

From the foregoing description, taken in connection with the drawings, the construction and

mode of operation of the invention will be readily understood without a further and extended description, and it will be seen that the invention provides a container car and construction of container whereby a large number of containers may be mounted on a standard sized car and arranged so that a plurality of containers may be held in each container compartment, thus allowing a maximum number of containers for articles up to a given size to be mounted on the car. These 10 containers may be so constructed that different kinds of materials, or different lots of the same material, may be stored and shipped in each container and the lots kept separate from each other, while affording greater convenience in 15 storing and removing the lots of goods. Other advantages of the invention will also be understood and appreciated by those versed in the art.

While the constructions of the parts herein shown are preferred, it is to be understood that 20 changes in the form, proportion and details of construction of the parts may be made, within the scope of the appended claims, without departing from the spirit or sacrificing any of the 25 advantages of the invention.

What I claim is:—

1. A container car having end walls, bulkheads arranged in spaced relation between the end walls and cooperating therewith to divide the car into transverse compartments, sockets in the floor of each compartment adjacent to the ends of the end walls and the bulkheads, filler blocks fitted in said sockets, posts secured to said filler blocks, rails carried by said posts and disposed in spaced relation to the end walls and bulkheads, and other 30 sockets arranged in each compartment between the rails therein to provide a set of retainer sockets in each compartment on opposite sides of the longitudinal center of the car.

2. A container car having bulkheads arranged in spaced relation to divide the car into transverse compartments, sockets in the floor of each compartment, filler blocks fitted in said sockets, posts secured to said filler blocks, rails carried by said posts and disposed in spaced relation to the 45 bulkheads, and other sockets arranged in each compartment between the rails therein to provide a set of retainer sockets in each compartment on opposite sides of the longitudinal center of the car.

3. In a gondola car having a longitudinal series of transverse container receiving compartments separated by transverse partitions spaced to provide longitudinal-shift-preventing abutments for containers of predetermined width, container leg 50 receiving sockets secured to the floor of the car adjacent to said abutments, attachment members applied at the sides of a compartment and comprising posts fitted and secured at their lower ends in said sockets, rails carried by the posts 55 and braces connecting said rails with the abutments, the rails being arranged parallel with each other and with the abutments and forming auxiliary longitudinal-shift-preventing abutments 60 for a container of relatively less width, and auxiliary sockets secured to the floor of the car and arranged in duplicate on opposite sides of the longitudinal center of said compartment for receiving the legs of a plurality of containers of 65 the lesser size.

GRAHAM C. WOODRUFF.
